 BUCKET ADAPTOR
 Frederick Loyal Smithee, 9326 Emiley St.,
 Elk Grove, Calif.
 Filed Nov. 9, 1962, Ser. No. 236,567
 10 Claims. (Cl. 182—2)

This invention relates to a bucket adaptor and relates more particularly to a man-carrying utility bucket lift adaptable to a truck-mounted hydraulic boom.

It is conventional in many industries, particularly the utility industry, to provide a truck-mounted liftable boom for raising poles such as telephone poles to a vertical position extending high above the ground level. It is also well known in many industries to provide a truck-mounted man-carrying utility bucket liftable to any of a variety of positions for reaching distant objects such as telephone wires, trees or the like. However, heretofore it has been necessary to provide separate vehicles for each of these respective functions.

It is an object of the instant invention to provide a man-carrying utility bucket lift which may be mounted as an accessory on a conventional hydraulic boom without interfering with the use of the boom for its ordinary purposes.

Another object of the instant invention is to provide such a device which makes use of the hydraulic extension of the boom itself for additional lift.

A further object of this invention is the provision of a device of the type described having means to raise or lower it vertically and to turn it in either direction horizontally to position the bucket in any desired location.

A still further object of this invention is to provide an adaptable utility bucket lift wherein the pivotal mounting for the bucket adaptor is always maintained in a horizontal position regardless of the position of the boom to facilitate positioning the bucket.

Another object of this invention is the provision of such a device wherein all the elements which might come in contact with live electrical wires are insulated to protect the equipment and the operator.

A further object of the instant invention is to provide a device of the character described which is comparatively inexpensive to manufacture, sturdy in construction and simple and efficient in operation.

Other and further objects reside in the combination of elements, arrangements of parts and features of construction.

Still other objects will in part be obvious and will in part be pointed out as the description of the invention proceeds and as shown in the accompanying drawings wherein there are disclosed preferred embodiments of this inventive concept.

In the drawings:

FIGURE 1 is a side elevational view of the device of the instant invention secured to a truck-mounted boom, alternative positions of adjustment being shown in dotted lines;

FIGURE 2 is an enlarged elevational view of the boom and bucket in accordance with the instant invention, partially broken away for illustrative convenience;

FIGURE 3 is a top plan view of a boom in transporting position as shown in dotted lines in FIG. 1 carrying the bucket adaptor of the instant invention, with parts being broken away;

FIGURE 4 is a side elevational view of the boom and bucket as shown in FIG. 3;

FIGURE 5 is a fragmentary transverse cross-sectional view taken substantially along line 5—5 of FIG. 4;

FIGURE 6 is a right end view of FIG. 5 showing the bucket turned at ninety degrees in dotted lines;

2

FIGURE 7 is a cross-sectional view taken along line 7—7 of FIG. 5;

FIGURE 8 is a cross-sectional view taken along line 8—8 of FIG. 5, with parts broken away;

FIGURE 9 is an enlarged top plan view of a portion of the device of the instant invention, partly in section and with parts broken away for illustrative convenience;

FIGURE 10 is a side elevational view of the portion of the device shown in FIG. 9;

FIG. 11 is a longitudinal cross-sectional view taken along line 11—11 of FIG. 9; and

FIGURE 12 is a fragmentary detailed sectional view of portions of the construction shown in FIG. 9.

Like reference characters refer to like parts throughout the several views of the drawings.

Referring now to the drawings in detail and more particularly to FIGURES 1, 3 and 4, a conventional utility truck is shown generally at 10 having a boom 12 pivotally mounted at 14 on the roof thereof with a pair of hydraulic cylinders 16 having their piston rods 18 operatively connected on either side of the boom 12 to raise and lower the same in the well known manner.

The man-carrying utility bucket adaptor of the instant invention is indicated generally by reference numeral 20 and is affixed to the upper extremity of the boom 12 by any conventional brackets such as 22 or the like. A hydraulic line 24 provides motive power to a number of cylinders to be described further hereinafter and is connected to the same system (not shown) which operates the hydraulic cylinders 16 of the boom 12.

The device of the instant invention is highly maneuverable and extremely flexible and is comprised of five basic components, the base member 26, the pivot member 28, the swivel head 30, the bucket support arm 32 and the utility bucket 34.

The base member 26 is generally a cylindrical element having a plurality of flanges 35 secured to the brackets 22 for supporting the device of the instant invention on the boom 12. The outer diameter of the base member 26 is slightly less than the distance between a pair of outstanding ears 36 forming a bifurcated end of the pivot member 28. Note particularly FIGURES 9 and 12. A pin 37 pivotally supports the base member 26 within the ears 36 of the pivot member 28.

A hydraulic cylinder 38 is pivotally supported at one end on the pivot member 28 and has a piston rod 39 pivotally secured at the opposite end to a bifurcated ear 40 fixed to the base member 26. A weighted pendulum 41 actuates a hydraulic control valve 43 to operate the hydraulic cylinder 38 to maintain the pivot member 28 in a vertical position as shown in FIGS. 1 and 2 regardless of the position of the boom. The construction of this element is conventional and will not be set forth in detail. The control valve 43 has a manual neutral or "off" position in the form of a lock (not shown) on the pendulum 41 in the center position. A by-pass emergency control valve may also be located in the bucket 34 or in a convenience position on the truck 10 to override the actuation of the hydraulic control valve 43 by the pendulum 41 in the manner described hereinbefore. By maintaining the pivot member 28 in the vertical position shown, rotating the device of the instant invention and positioning of the bucket 34 by the operator is greatly facilitated as will be clearly seen from the remainder of the disclosure.

The swivel head 30 is formed in the shape of a right angle and has a horizontal swivel 42 which is rotatably supported with respect to the pivot member 28. A hollow extension 44 of the horizontal swivel 42 passes through holes defined in pivot member 28 and has an outstanding flange 46 fixed adjacent a threaded end 48 forming a race way with an element 50 fixed to the pivot head 28 to support a plurality of thrust bearings 52. Ball bearings 54

are also interposed between the swivel head 30 and the pivot member 28 to assist in relative rotation of the two elements. A washer, nut and lock nut 55, 57 and 59 respectively, secure the swivel head 30 to the pivot member 28.

These elements are rotated relative to each other to swing the bucket 34 horizontally relatively to the ground by means of the hydraulic cylinder 56 and the steel cable 58. The hydraulic cylinder 56 and a pulley 60 are rotatably or oscillatably supported with respect to the base member 26 by a pin or the like 62. A bracket 64 is fixed to the pin 37 and rotatably supports a plurality of aligning pulleys 66. An additional pair of pulleys 68 are rotatably supported by brackets 70 in a position adjacent horizontal swivel head 42. The steel cable 58 passes over the pulley 60, through the aligning pulleys 66 and over each of the additional pulleys 68 and is wound a plurality of times around the horizontal swivel 42. The piston rod 72 of the hydraulic cylinder 56 has a connector element 74 interposed between the two ends of the steel cable 58. When the piston rod 72 of the hydraulic cylinder 56 is extended, the steel cable 58 is pushed by the piston rod 72 and the frictional drag between the steel cable 58 and the horizontal swivel 42 causes relative rotation between the pivot member 28 and the swivel head 30.

It is to be noted that for illustrative convenience the bucket support arm 32 has been shown relatively close to the base member 26 in FIGS. 3 and 9, but that in order for complete rotation about the horizontal swivel 42 to be effected, sufficient distance must be allowed between these elements so that the bucket support arm 32 will not contact the base member 26 or the pivot member 28 during rotation.

The swivel head 30 is connected to the bucket support arm 32 by a hollow pin 76 secured by a washer, nut and lock nut 78, 80 and 82 respectively. The hydraulic line 24 passes through a tunnel 84 in the swivel head 30 and an opening 86 in the hollow pin 76 and extends out through the end of the pin 76 to return to the center of the steel arm 88 forming part of the bucket support arm 32 through the opening 90. Note FIG. 9.

A vertical swivel 92 rotatably connects the swivel head 30 and the bucket support arm 32 to allow the latter to be swung in almost a complete circle about the pin 76. A hydraulic cylinder 94 and a steel cable 96 cause the relative rotation of these parts in a manner similar to the rotation of the horizontal swivel 42. The steel cable 96 passes over a pulley 98 rotatably fixed to the steel arm 88 and a connector element 100 operatively secures the piston rod 102 of the hydraulic cylinder 94 to the steel cable 96. The hydraulic cylinder 94 is pivotally secured to the steel arm 88 at 104 and the steel cable 96 is wrapped around the vertical swivel 92 several times to frictionally engage the same. Extension of the piston rod 102 of the hydraulic cylinder 94 will cause the frictional engagement of the steel cable 96 to rotate the bucket support arm 32 relative to the swivel head 30.

An insulated hood 106 and extension 108 circumscribe the major portion of the steel arm 88 and the operating elements for the vertical swivel 92 to avoid any possible contact with live electrical wires and subsequent damage to the equipment. Any well known material such as fiber glass or plastic may be useful for these elements.

At the top of the end of the extension 108 the bucket 34 is pivotally secured by a pivot pin 110 in such a manner that the center of gravity will always lie below the pin and will retain the bucket 34 in a vertical position as shown in FIGURES 1 and 2. A control box 112 is secured to the swivel pin 110 and the bucket 34 will have brackets 114 to readily detach the same from the control box. The bucket 34 is preferably made of insulated material similar to the hood 106 and extension 108 for the protection of the operator and may have a roughened flooring such as indicated at 116 in FIGURE 6 to reduce

slipping. A plurality of control levers 118 may extend from the control box 112 within easy reach of the operator to facilitate his directing the bucket 34 to any position necessary for him to perform his job. Four such levers 118 are shown as illustrative but any desired number may obviously be included. It is necessary to provide means to control vertical movement of the boom 12 through the hydraulic cylinders 16, rotation of the horizontal swivel 42 by the hydraulic cylinder 56, rotation of the vertical swivel 92 by the hydraulic cylinder 94 and a bypass for manual control of the hydraulic cylinder 38 to rotate the pivot member 28 with respect to the base member 26 and override the hydraulic control valve 43.

It is to be noted that a padded element 120 is provided on the roof of the truck 10 to support the device of the instant invention when the same is not in use as shown particularly in FIGURES 1 and 4. Any additional support brackets may be included if desired. Any conventional means may be attached to the bucket 34 to maintain the same in the horizontal position shown in FIGURES 1, 3 and 4 when the truck 10 is being moved.

A duplicate set of controls will necessarily be included in some convenient location within or on the truck 10 so that the device of the instant invention may be operated from the ground.

From the foregoing description the use and operation of the device of the instant invention will now be apparent. The truck 10 may be driven to the general location where overhead wires require maintenance or where some other operation above the ground is necessary. When the truck 10 is positioned the device of the instant invention may be raised from its traveling position shown in dotted lines at 122 in FIG. 1 to its mounting position shown in dotted lines at 124 in FIG. 1 where the bucket 34 is near the ground and the rear of the truck 10 for easy mounting by an operator. Maneuvering of the device to the position 124 is accomplished by the aforementioned duplicate set of controls.

Once the operator has gotten into the bucket 34 he may maneuver it by the control levers 118 to any desired working position. By extending the hydraulic cylinders 16 the boom 12 will be raised to the position shown in FIG. 1 which is the normal operating position of the device of the instant invention and then by relative operation of the hydraulic cylinders 56 and 94 via the control levers 118 the operator may maneuver the bucket 34 both vertically and horizontally. The pivot member 28 will always be maintained in its horizontal position shown in FIGURE 1 by the operation of the hydraulic cylinder 38 through the force of gravity on the weighted pendulum 41 and the aforementioned hydraulic control valve (not shown). If the operator desires to override the gravity operated control valve he may do so.

It will be noted that the device of the instant invention may be quickly and easily mounted on the ordinary boom 12 of the truck 10 and will in no way interfere with normal operation of this boom for setting telephone poles or the like. Through the use of the device of the instant invention a single truck may be used to provide the function of the ordinary truck-mounted boom plus the function of the ordinary truck-mounted man-carrying utility bucket.

From the foregoing it will be seen that there is herein provided a device which accomplishes all of the objects of the instant invention and others including many advantages of great practical utility and commercial importance.

Since many embodiments may be made of this inventive concept and since many modifications may be made in the embodiments hereinbefore shown and described it is to be understood that all matter herein is to be interpreted as merely illustrative and not in a limiting sense.

I claim:

1. In a truck having a pivotally mounted boom and means to raise and lower said boom, a utility bucket hav-

ing a center of gravity and being adapted to carry a man, elongated supporting means having two ends and carrying said utility bucket at one end thereof, means to detachably secure the other end of said supporting means to said boom, a horizontal swivel intermediate the ends of said supporting means for swiveling the said bucket in a horizontal plane, a vertical swivel intermediate the ends of said supporting means for swiveling said bucket in a vertical plane and means actuatable from said utility bucket to operate said horizontal and vertical swivels, said elongated supporting means including a base member, a pivot member pivotally secured to said base member, a swivel head rotatably secured to said pivot member by said horizontal swivel, and a bucket support arm rotatably secured to said swivel head by said vertical swivel, said utility bucket being pivotally mounted above its center of gravity on said bucket support arm.

2. A device in accordance with claim 1 wherein said elongated supporting means is electrically insulated throughout a major portion of its length.

3. A device in accordance with claim 1 wherein said utility bucket is formed of an electrically insulating material.

4. A device in accordance with claim 1 wherein a duplicate set of means are provided in said truck to operate said horizontal and vertical swivels.

5. A device in accordance with claim 1 further including means to maintain said pivot member in a vertical position regardless of the position of said boom.

6. A device in accordance with claim 5 wherein said means to maintain said pivot member in said vertical position includes a hydraulic cylinder having two ends and being pivotally connected at one end to said pivot member and having a piston rod extending from its other end, said piston rod being pivotally secured to said base member, a hydraulic control valve operatively connected to said cylinder, and a pivotally supported weighted pendulum operatively connected to said hydraulic control valve to actuate the same.

7. A device in accordance with claim 5 wherein said means to actuate said vertical swivel includes a hydraulic cylinder having two ends and being pivotally connected at one to said bucket support arm and having a piston rod extending from its other end, a pulley rotatably sup-

10
15

ported on said bucket support arm, a cable means having two ends, one end of said cable means passing over said pulley and the other end of said cable means being wrapped around said vertical swivel a plurality of times to frictionally engage the same and a connector element securing both ends of said cable means to said piston rod.

8. A device in accordance with claim 5 wherein said means to actuate said horizontal swivel includes a hydraulic cylinder having two ends and being pivotally connected at one end to said base member and having a piston rod extending from its other end, a first pulley rotatably supported on said base member, a cable means having two ends, one end of said cable means passing over said first pulley and the other end of said cable means being wrapped around said horizontal swivel a plurality of times to frictionally engage the same and a connector element securing both ends of said cable means to said piston rod.

9. A device in accordance with claim 8 further including aligning means to maintain said other end of said cable means in substantially parallel alignment as it approaches and leaves said horizontal swivel regardless of the relationship of said base member, pivot member and swivel head.

10. A device in accordance with claim 9 wherein said aligning means includes a bracket carrying two pairs of vertically spaced second pulleys, said bracket being fixed to said pivot member and a pair of third pulleys rotatably supported on said pivot member adjacent said horizontal swivel, said other end of said cable means passing between one pair of said second pulleys and over one of said third pulleys before being wrapped around said horizontal swivel and passing over the other of said third pulleys and between the other pair of said second pulleys before being secured to said connector element.
